UNITED STATES PATENT OFFICE.

THOMAS GEORGE STILES, OF ARLINGTON, NEW JERSEY.

SWITCH MECHANISM.

1,253,439.

Specification of Letters Patent. Patented Jan. 15, 1918.

Application filed October 9, 1915. Serial No. 54,971.

To all whom it may concern:

Be it known that I, THOMAS GEORGE STILES, a citizen of the United States, and resident of Arlington, in the county of Hudson and State of New Jersey, have invented certain new and useful Improvements in Switch Mechanism, of which the following is a specification.

This invention relates to improvements in switch-mechanism, and particularly to the front-rod and the locking devices associated therewith.

One of the principal objects of the invention is to provide a switch-mechanism having a front-rod so constructed as to be readily adjustable to space the points of the switch-rails at the desired distance apart and to have this spacing changed when required as the result of wear, etc. Such a front-rod may be made in sections, with engaging, transverse serrations at their adjacent ends, by means of which serrations the sections will be prevented from having relative movement lengthwise of the front-rod when held in place by suitable securing devices. An important feature of this front-rod is that it is also preferably oblong in cross-section, so that when its major axis is vertically disposed simple fastening devices, such as bolts, may be passed through openings in the rod, without substantially weakening such rod, and connections made to various devices intended to operate or to be operated by the switch.

Another important object of the invention is to provide an improved plunger lock for the lock-rod connected to the front-rod, this mechanism comprising a lock-rod also rectangular and flat in cross-section, and adapted to coöperate with a plunger movable transversely thereto which plunger is also preferably rectangular and flat in cross-section; the point of intersection of the lock-rod and its locking plunger being, as is usual, protected by a suitable casing which in this instance has an inspection opening making examination of the lock convenient at all times.

Another feature of the invention relates to the universal connection with the front-rod of certain operating and operated members; and various other features of construction will be hereinafter described, and claimed, and are illustrated in the accompanying drawings, in which—

Figure 1 is a plan of a switch-mechanism embodying my present invention.

Fig. 2 is a vertical, transverse section of the same, the section being taken in line 2—2 Fig. 1.

Fig. 3 is an enlarged, broken plan of the front-rod of Fig. 1, slightly modified and illustrating various connections which may be made thereto.

Fig. 4 is an enlarged, broken elevation of the same.

Figs. 5 and 6 are details of coupling-lugs for connections to the front-rod.

Fig. 7 is an enlarged plan of the plunger lock.

Fig. 8 is an end elevation of the same, looking from the right in Fig. 7.

Similar characters designate like parts in all the figures of the drawings.

Referring first to Fig. 1, 3—3 designate a pair of stock-rails and 4—4 a pair of point-rails of a switch, the stock-rails being supported on suitable ties 5, or otherwise, and braced in a manner that is well understood by rail-braces of the type indicated at 6, or of any other suitable type.

The points of the switch-rails are connected as usual by means of a front-rod, but the front-rod shown differs in various ways from the front-rod usually employed. The front-rod illustrated is preferably a member rectangular in cross-section, as, for example, with the major axis vertically disposed. One object of this is to permit said front-rod to be bored to receive suitable devices for connecting to the front-rod a part or parts to operate or to be operated by the switch. This front-rod is also preferably made in sections in order that it may be adjustable in length. Here there are two main sections adapted to have relative adjustment lengthwise of the front-rod, these sections being designated by 7 and 8 and the rod itself by 9. At the ends thereof these sections are shown as bent around at substantially a right angle to the rod proper to provide means of connection with the inner sides of the switch-rails near the points thereof. It will be seen that by making the front-rod oblong in cross-section a relatively wide and flat surface is provided on each of the bent portions 9 and 10 of the front-rod for engagement with the inner vertical sides of web portions of the switch-rails. By means of suitable bolts and nuts,

110

such as indicated at 11 and 12, these bent ends of my improved front-rod may be securely fastened to the switch-rails. Suitable washers are shown on the inner sides 5 of the ends of this front-rod at 45 and 46 in Fig. 3.

It will be obvious that a front-rod constructed as just described will be quite stiff vertically in the direction in which stiffness 10 is required in such a device. When the front-rod is made in sections, as shown in the drawings, this stiffness is retained by providing suitable connections at the meeting surfaces of adjacent rod sections. The 15 preferred connection is one permitting relative adjustment of the sections lengthwise of the rod, the construction shown being one in which the adjacent vertical surfaces of the inner ends of the rod-sections are serrated so that the serrations may engage in 20 different positions lengthwise of the rod and maintain any desired adjustment when held together by means of suitable clamping devices. Here the section 7 has vertical 25 serrations or teeth 7' and the section 8 has corresponding serrations or teeth 8' all disposed vertically and formed in the relatively flat sides of the rod-sections. The oblong cross-section before referred to also provides for the use of relatively long serrations 30 adapted to hold the two sections of the front-rod positively in alignment when locked together. Suitable bolts and nuts are shown at 13 and 14 for this purpose. The 35 bolts 13 pass through suitable openings in the rod-sections which openings in order to permit relative adjustment of said sections lengthwise of the front-rod are some of them elongated, as shown at 15. Any desired 40 change in adjustment may be obtained that is within the limits of this slot 15.

My improved front-rod is also preferably an insulated rod, as before stated. In the 45 present case the main section 8 is made up of two parts connected by an insulating joint. Here this insulating joint is formed by the flat plate portion 16 of a lug 17 and a corresponding plate 18, coöperative with the flat portion 16 of the lug and held 50 to it and also to the adjacent ends of the two parts of the rod-section 8 by suitable bolts, 19, and nuts, 20, securing in place between them also insulation, such as shown at *i* (Fig. 3). Suitable washers are also 55 disposed between the nuts 20 and plate 18, as shown at 21. By means of these elements a strong connection mechanically is formed between the two parts of the rod-section 8 and at the same time they are electrically 60 insulated from each other and from the lug 17 itself, which is intended to constitute a coupling for connecting to the front-rod a suitable operating or operated member, in this case a lock-rod, such as 22.

65 Part 17 is one of a plurality of couplings

which may be employed for connecting the front-rod to different operating and operated elements, and the lug 17 is also illustrated as so constructed as to constitute a universal connection between the front-rod 70 and the connected element to operate or to be operated by said front-rod. Here various parts are connected to the front-rod and two of these are shown as having universal connection therewith. The other universal connection illustrated is embodied in a coupling 75 also formed as a lug attachable to or detachable from the front-rod, said lug being indicated at 23. This lug is also preferably secured to the front-rod in substantially the same manner as lug 17, except that there is no interposed insulation between the lug and the front-rod. The securing devices are shown as bolts and nuts 24 and 25, with interposed washers 26. Each of the lugs 17 80 and 23 is illustrated as bored in such a manner that the axis of the bore extends substantially in the same general direction as the front-rod, but is parallel with said front-rod, and each of said bores tapers, the taper 85 being preferably a double one and extending from the opposite ends of the bore to the center thereof, as clearly illustrated in Fig. 3, at 27 and 28. Two of said bores are shown in the lug 23 for the purpose of making 90 universal connection when desired with two different rods. Lug 17 is intended for connection to the lock-rod extending to the plunger lock and lug 23 is intended for connection with a bolt lock. At 29 is also shown 95 a simple connection for a rod 30 extending to a switch-box. All of the connections just described are intended to permit adjustment of the different rods lengthwise thereof, each 100 of them being shown as having suitable adjusting and check nuts. In addition, each of the rods passing through one of the tapered bores 27 or 28 is of course also cylindrical and unthreaded at its point of contact with said surfaces 27 and 28, in order to permit proper, relative, universal movement. 105

Another important feature of the invention is the improved plunger lock before mentioned. The lock-rod itself, indicated at 22, extends to the locking point substantially flat or oblong in cross-section for the major portion of its length and has relatively long locking notches, 31, the length of which may be varied by a suitable adjusting bar, 32, the position of which may be determined at one end by a bolt and nut, 33 and 34, and at the other end by suitable adjusting and check nuts, designated generally by 35. The manner in which this adjustment is obtained will be clear by reference to Figs. 1 and 2. Into the notches 31 so formed is adapted to pass a plunger *p* mounted on a suitable base 36, substantially in the well known manner, this base being in turn supported on a plate 37 secured to 110 115 120 125 130

the ties 5. A cover 38 is bolted down on this base in the usual manner as shown in Figs. 1, 2, 7 and 8 and forms with said base a casing on which the lock-rod and its locking plunger are movable in directions transverse to each other. Provision is made in the construction illustrated for permitting some lateral rocking movement of the lock-rod, the base casting having a suitably 10 tapered opening in which the lock-rod works. The plunger of this plunger-lock differs however from those heretofore employed and is rectangular or preferably oblong in cross-section, so as to form a flat 15 locking plunger which will not turn in its supporting casing and will present a wide flat end with horizontal and perpendicular faces for entering into the lock-notches 31 of the lock-rod 22. A further important 20 feature of the construction is that the casing formed by the base casting, 36, and the cover, 38, is not closed so that the locking point, that is the point of crossing of the lock-rod and the plunger, is invisible, but 25 is formed with an inspection opening, 40, in the cover, 38, and this opening is intended to be covered and uncovered by a suitable hinged cover member, such as 41, supported on the plate 38. This cover member may of 30 course be locked in place if desired. When the cover is thrown back it will be easy to see at a glance just what the condition of the lock is at the locking point and any undue wear that has taken place may be 35 instantly detected and suitable adjustment of the parts made.

In substantially the same manner wear at the switch-point and at the connections of the various rods with the corresponding lugs 40 attached thereto may also be readily taken up at any time.

It is desirable to utilize the plunger lock as a means for controlling an electric circuit and bring about the energization and de- 45 energization of the same according as the lock-rod of the switch-mechanism is locked or unlocked by the plunger. In order to accomplish this result I have illustrated an insulated contact, 42, at a suitable point on 50 the plunger *p* and a co-operative fixed contact, 43, on the base casting. The contact 42 will be in engagement with the contact 43 and a suitable circuit therethrough (not shown) will be closed when the lock-rod is 55 locked by said plunger, and the contact 42 will be shifted out of engagement with the contact 43 to open said circuit when the plunger is withdrawn from its lock-notch in the lock-rod.

60 What I claim is:

1. In a switch-mechanism, the combination with a pair of switch-rails, of a front-rod connecting the same and comprising a pair of sections substantially oblong in cross-section with the major axis vertical, said rod

sections being adjustable longitudinally of each other and having at their adjacent ends complementary engaging serrations extending completely across one of the wider sides thereof, and means for holding the serrated 70 portions of said rod-sections in any adjusted position.

2. In a switch-mechanism, the combination with a pair of switch-rails, of a front-rod, said front-rod comprising a pair of 75 sections adjustable longitudinally of each other and having at their adjacent ends complementary engaging transverse serrations, and having at the remote ends integral portions extending in angular relation 80 thereto and connected to the inner sides of the rails, and means for holding the serrated portions of said rod-sections in any adjusted position.

3. In a switch-mechanism, the combination with a pair of switch-rails, of a front-rod connecting the same and comprising a pair of sections adjustable longitudinally of each other and having at their adjacent ends complementary engaging serrations, means 90 for holding the serrated portions of said rod-sections in any adjusted position, and a coupling secured to and extending in angular relation to said front-rod and connected to another rod to be operated. 95

4. In a switch-mechanism, the combination with a pair of switch-rails, of a front-rod connecting the same and comprising a pair of sections adjustable longitudinally of each other and having at their adjacent ends 100 complementary engaging serrations, means for holding the serrated portions of said rod-sections in any adjusted position, and a plurality of couplings secured to said front-rod at different points in the length of the 105 latter and connected respectively to a plurality of rods to be operated.

5. In a switch-mechanism, the combination with a pair of switch-rails, of a front-rod connecting the same and comprising a 110 pair of sections adjustable longitudinally of each other and having at their adjacent ends complementary engaging serrations, means for holding the serrated portions of said rod-sections in any adjusted position, and a 115 coupling secured to said front-rod, a rod to be operated, and a universal connection between said coupling and the rod to be operated.

6. In a switch-mechanism, the combination with a pair of switch-rails, of a front-rod connecting the same and comprising a pair of sections adjustable longitudinally of each other and having at their adjacent ends 120 complementary engaging serrations, means for holding the serrated portions of said rod-sections in any adjusted position, and a plurality of couplings secured to said front-rod at different points in the length of the latter, a plurality of rods to be operated 125 130

- which rods run in different directions, and a plurality of universal connections between said respective couplings and the respective rods to be operated.
- 5 7. In a switch-mechanism, the combination with a pair of switch-rails, of a front-rod connecting the same and comprising a pair of sections, a combined insulating coupling including means for connecting the sections together and a universal joint, and a rod to be operated connected to said front-rod by said universal-joint.
- 10 8. In a switch-mechanism, the combination with a pair of switch-rails, of a front-rod connecting the same, a coupling member secured to said front-rod and having a bore substantially parallel with said front-rod and tapering toward one of its ends, a second rod mounted in said bore and having a portion coöoperating with said bore to form a universal joint, and means for holding said second rod in place in said coupling.
- 15 9. In a switch-mechanism, the combination with a pair of switch-rails, of a front-rod connecting the same, a coupling member secured to said front-rod and having a bore substantially parallel with said front-rod and tapering in two directions toward its center, a second rod mounted in said bore and having a portion coöoperating with said bore to form a universal joint, and means for holding said second rod in place in said coupling.
- 20 10. In a switch-mechanism, the combination with a pair of switch-rails, of a front-rod connecting the same, and switch-locking means comprising a lock-rod, a connection between said front-rod and lock-rod, a locking plunger movable transversely to and co-operative with said lock-rod at the locking

point, and a casing covering the locking point and having an inspection opening at such point.

11. In a switch-mechanism, the combination with a pair of switch-rails, of a front-rod connecting the same, and switch-locking means comprising a lock-rod, a connection between said front-rod and lock-rod, a locking plunger movable transversely to and co-operative with said lock-rod at the locking point, and a casing covering the locking point and having an inspection opening at such point with a hinged door for covering and uncovering said opening.

12. In a switch-mechanism, the combination with a base having intersecting longitudinal and transverse passages and one of which has tapered walls to permit sidewise movement of the lock-rod, of a plunger movable in said base in one direction, and a lock-rod movable in said base in a direction transverse to the plunger and also having cross-wise movement.

13. In a railway switch lock device, the combination with the switch tongues, and a lock bar in operative connection therewith, of a lock device composed of two parts secured together and through which said lock bar passes, and a plunger bar movable through said lock device transversely of said lock bar and in operative connection therewith.

Signed at New York in the county of New York and State of New York this 5th day of October, A. D. 1915.

THOMAS GEORGE STILES.
